PHONOGRAPH TONE ARM

William E. Stacy, North Wilbraham, Mass., assignor to
The Poly-Choke Company, Inc., East Hartford, Conn.,
a corporation of Connecticut

Filed Dec. 18, 1967, Ser. No. 9,824

Term of patent 14 years

U.S. Cl. D26—14
Int. Cl. D14—01

FIG. 1 is a perspective view of a phonograph tone arm of the present design;

FIGURE 2 is a top plan view; and

FIGURE 3 is a side elevation view thereof.

The dominant features of my design reside in the full line portions.

I claim:

The ornamental design for a phonograph tone arm, substantially as shown and described.
